LIQUID FLOW CONTROL VALVE

Gordon Edwards, Victoria, British Columbia, Canada

Application August 31, 1953, Serial No. 377,665

6 Claims. (Cl. 137—119)

This invention relates generally to control valves, and more particularly to a liquid control valve of the type which has an inlet and a plurality of outlet ports and which is designed to direct a liquid, which enters the inlet port under pressure, to each of the outlet ports in turn and for a predetermined time interval.

Valves of this type are known, as may be readily ascertained by reference to the records of the United States Patent Office, and especially class 299, sub-class 27, and class 137, sub-class 119, as presently constituted. Examples of this type of valve are disclosed in U. S. Patent 1,753,240, W. Howell et al.; U. S. Patent 2,081,510, K. R. Smart; U. S. Patent 1,004,726, L. D. Barney; and U. S. Patent 1,889,858, E. Greene et al. This type of valve is useful in many varied applications, intermittent operation of groups of sprinklers in gardens or orchards; intermittent flushing of urinals in office buildings; and intermittent supplying of drinking water to troughs located at various points in a livestock farm; being but a few of a host of possible uses.

The liquid flow control valve of my invention is of a simple yet rugged construction. Its operation is controlled by the pressure of a liquid fed through its inlet port, and it will operate equally well whether the liquid comes from a low pressure source, such as is available from a conventional household tap, or a high pressure source, such as a high pressure pump. The device includes a train of reducing gears, a bladed wheel to drive one member of said train, and an outlet port actuating camshaft driven by another member of said train. It is of course possible to drive the camshaft from selected members of said train revolving at different speeds, and this increases the versatility of performance of the device.

My contribution to this art may be generally defined as a liquid flow control valve comprising a liquid-tight casing divided into two compartments; a single inlet port in one of said compartments; a plurality of outlet ports in the other of said compartments; at least one port permitting liquid flow between said one compartment and said other compartment, and mechanism for directing to each of the outlet ports in turn, and for a predetermined interval of time, a liquid which enters said inlet port under pressure. This directing mechanism comprises a bladed wheel rotatably mounted within said one compartment in a position where liquid which enters the inlet port under pressure will impinge upon the blades of the wheel and cause the wheel to rotate; a train of reducing gears mounted within said casing; a camshaft rotatably mounted within said other compartment, the camshaft carrying at least one cam, said cam having an arcuate camming surface; the bladed wheel being operatively connected to one of the gears of said train, and the camshaft being operatively connected to a relatively slow-moving member of said train, whereby the camshaft rotates slowly, as compared to said bladed wheel, whenever the bladed wheel is rotated by liquid entering the inlet port under pressure; a strip of resilient material associated with each

2

outlet port, one end of each of said strips being mounted at a point adjacent the inner wall of said other compartment, each of said strips being swingable about its point of mounting from a position in which it seals its associated outlet port to a position in which it permits flow therethrough; a spring associated with each of said strips, said springs normally biasing said strips to occupy positions in which they seal the outlet ports; each of said strips extending beyond its associated outlet port, in a direction away from its point of mounting, for a distance sufficient to enable said cam to contact the strip and peel it back from its spring-pressed port-sealing position once during each complete revolution of the camshaft.

The outlet ports may be opened by a single cam attached to the camshaft; or a plurality of cams may be employed, whereby the different ports may be opened for different lengths of time. These features will be described in more detail later on in this specification.

In the accompanying drawings which illustrate embodiments of my invention;

Figure 1 is a central vertical cross-section through one embodiment;

Figure 2 is a view of the bottom of the device shown in Figure 1 with the bottom cover removed so as to better show the interior of the outlet section of the valve;

Figure 3 is a view of the top portion of the device shown in Figure 1 with the cover removed in order to better show the inlet section of the valve;

Figure 4 shows, on an enlarged scale, the outlet ports and a camshaft with a group of four cams which, according to a second embodiment of the invention, may be substituted for the camshaft and single cam shown in Figures 1 and 2;

Figure 5 is a side view of the device shown in Figure 4, the view in Figure 5 additionally showing parts of the camshaft drive and the casing.

Figure 6 is a top plan view of the four cams employed in Figures 4 and 5;

Figure 7 is a view showing the four cams which could be used in the case of a third embodiment of the invention, in which four outlet ports are opened and turned by a group of four similar cams, the arrangement being such that all the ports are successively open for the same interval of time.

Turning first to the embodiment of the invention shown in Figures 1, 2 and 3, reference numeral 10 generally indicates a liquid-tight casing having a cylindrical side wall 11; a removable lid 12, and a removable base 13. Lid 12 and base 13 are bolted to the cylindrical body 11, as shown at the points labelled 14. Rubber gaskets 15 are employed to make sure the casing is water-tight when assembled.

The casing 10 is divided into an upper compartment 16 and a lower compartment 17 by a horizontal wall 18. Wall 18 is provided with two ports 19 which permit liquid flow between the compartments 16 and 17 of the casing. A single inlet 20 is provided for upper compartment 16, while compartment 17 is provided with four outlets 21.

A bladed wheel 22 is mounted within upper compartment 16, the wheel being carried by a rotatably mounted shaft 23. The bladed wheel 22 is disposed adjacent the inlet 20 so that whenever liquid enters the inlet under pressure, the liquid will impinge on the blades of the wheel, causing it to rotate, together with its shaft 23. A train of reducing gears, generally indicated by reference number 24, is mounted within the casing just below the wall 18. I do not propose to describe this train of reducing gears in any detail since such arrangements are well known, and no special type of reducing gearing is called for in the practicing of my invention. A camshaft 25 is rotatably mounted in suitable bearings in the lower

compartment 17. Shaft 23 of bladed wheel 22 carries a pinion which meshes with one member of the train 24. Camshaft 25 carries at its upper end a gear wheel 26 which meshes with a member of the train of reducing gears 24, which is relatively slow moving, as compared to the gear driven by shaft 23. Thus, as will be readily understood, when bladed wheel 22 is caused to rotate by water entering inlet 20 under pressure, the camshaft 25 will be rotated through the train of reducing gears, but at a much slower speed than the wheel. The camshaft 25 shown in Figures 1 and 2 carries a single cam 27 which has an arcuate camming surface 28.

The outlets 21 consist of tubular members which extend through the cylindrical side wall of the lower compartment 17. The tubular members are threaded at their outer ends as indicated at 29, so that they may be coupled to delivery conduits for the liquid being passed through the valve. The inner ends of each of the tubular inlet members is vertically disposed, and these ends (which have been labelled 30 in Figure 1) constitute the four outlet ports for the valve.

A generally rectangular strip 31 of a resilient material, preferably rubber, is associated with each outlet port 30. One end of each strip 31 is swingably mounted on a pin 32, the pins being located parallel to and adjacent the inner side wall of the lower compartment 17. Each strip 31 is swingable on its pin 32 from a position in which it lies flushly against and seals the outlet port it is mounted adjacent to a position in which it permits flow of liquid through that port. A spring 33 is associated with each of the strips 31, the springs being positioned so as to normally bias the strips to occupy positions in which they seal the outlet ports 30.

Each of the strips 31 extends beyond its associated outlet port 30, in a direction away from the pin 32 for a distance sufficient to enable the cam 28 to contact the strip and peel it back from its spring-pressed port-sealing position as the camshaft 25 is rotated by the bladed wheel 22.

Preferably, as has been shown in Figures 1 and 2, the outlets 21, the outlet ports 30, and the strips 31 are equidistantly spaced around the lower compartment 17. The width of the cam at the end where the arcuate camming surface 28 is provided, i. e., the length of the arcuate camming surface, is preferably such that as the trailing edge of the cam releases one of said strips, its leading edge will contact and begin to peel open the next-adjacent strip 31 in the direction of rotation of the camshaft 25. With this preferred arrangement, one port 30 is always open to some extent; and since the outlet ports are equally spaced, each outlet port will be open for the same time interval, provided a constant pressure is available at the inlet port. The frequency with which the ports are opened is dependent upon the pressure of the liquid entering the port and the reduction ratio used in the train of gears 24. As will be readily understood, the speed at which the wheel 22 drives the camshaft 25 can be increased or decreased by making changes in the meshing relationship of the gearing 24.

Turning now to Figures 4 to 7, I first wish to point out that the main difference between the embodiment shown in these figures and the embodiments shown in Figures 1 and 2 is that the single cam 27 is replaced by four cams. These four cams have been labelled 27A, 27B, 27C and 27D in Figures 4 to 7, and their arcuate camming surfaces have been labelled 28A, 28B, 28C and 28D, respectively. In the case of Figures 4 and 6, the four cams are of unequal width, so that the cams have arcuate camming surfaces of differing lengths. In the case of Figure 7, the cams are of equal width and have arcuate camming surfaces of equal length. The cams 27A, 27B, 27C and 27D are mounted one above the other, on the camshaft 25.

The ends of the strips 31 nearest the cams are cut away,

as indicated at 34. By suitably cutting away portions of the strips, it is a simple matter to arrange for any given strip 31 to be contacted solely by the one member of the group of four cams which has been selected to control the opening of the given strip.

The total amount of arcuate camming surface provided by the four cams 27A, 27B, 27C and 27D—whether they have arcuate camming surfaces of unequal length as in Figures 4 to 6, or whether the cams are similar and have arcuate camming surfaces of similar length as in Figure 7—is substantially 360°. Moreover, the several camming surfaces 28A, 28B, 28C and 28D are arranged without overlapping when viewed in the direction of the axis of the camshaft 25. With this arrangement one strip will begin to be peeled open by one of the cams, just as another strip is released by its cam. Once a cam releases a strip, the strip is, just as in the case of Figures 1 and 2, pressed by its spring 33 into a port-sealing position. However, one port will be open at all times, since the cams are arranged without overlapping and their arcuate camming surfaces total substantially 360°.

The object, of course, of having the arcuate camming surfaces of different lengths, as shown in Figures 4, 5 and 6, is to provide for the opening of the different ports for different lengths of time. Thus, cam 27D (which has a much longer camming surface 28D than the camming surface 28A on cam 27A) would open its outlet port for an appreciably longer time than cam 27A would hold its port open.

I view the arrangement of Figure 7 as less preferable than the arrangement of Figures 4 to 6. According to Figure 7, the cams are similar and each have arcuate camming surfaces of the same length, with the result that the outlet ports controlled by these cams will each be opened for the same period of time. However, where flow through the outlet ports for equal lengths of time is the desideratum, I presently prefer to use the single cam arrangement shown in Figures 1 and 2.

With the exception of the use of four cams instead of the single cam of Figures 1 and 2, and the cutting away of the cam-actuated ends of the strips 31 of resilient material, the parts of the embodiments shown in Figures 4 to 7 inclusive would be exactly the same as the parts shown in Figures 1, 2 and 3. It is for that reason that I decided to show, in Figures 4 to 7, only the bare essentials and to omit those parts of the apparatus which are already adequately illustrated in Figures 1 to 3.

Before ending this specification, I would like to point out that the use of resilient material to form the sealing strips for the outlet ports is advantageous in that the strips are not initially moved away from the ports they seal as if they constituted a rigid gate, but instead bend near their outer ends as a result of the couple imposed upon them by the oppositely working forces of the (1) spring 33 which biases the strip towards the closed position and (2) the cam which is forcing the strip open. This bending gives a peeling action which allows liquid to initially escape slowly through the outlet port so that there is gradual, rather than sudden, equalization of pressure in the partition 17 and the outlet 21 which has just been opened.

While four outlets have been shown in the drawings, a larger or smaller number could obviously be employed without departing from the invention. Moreover, delivery of liquid to a multiplicity of points can be achieved by using several of the valves according to my invention. For example, by connecting the inlet of a valve similar to that shown in Figures 1 and 2 to a single water service line, connecting a similar valve to each outlet 21 of the line-connected valve, and connecting the outlets of these additional valves to sprinkler heads, water could be delivered sequentially to sixteen different sprinklers for predetermined equal intervals of time. Where it is desired to have some of the sprinklers fed for a longer period than others, the connections de-

scribed just above could be made with the exception that one or more of the valves shown in Figures 4 to 6 could be substituted for the valves according to Figures 1 and 2.

What I claim as my invention is:

1. A liquid flow control valve comprising a liquid-tight casing; a wall dividing said casing into two compartments; a single inlet port in one of said compartments; a plurality of outlet ports in the other of said compartments; at least one port permitting liquid flow between said one compartment and said other compartment; and mechanism for directing to each of the outlet ports in turn, and for a predetermined interval of time, a liquid which enters said inlet port under pressure, said mechanism comprising: a bladed wheel rotatably mounted within said one compartment in a position where liquid which enters the inlet port under pressure will impinge upon the blades of the wheel and cause the wheel to rotate; a train of reducing gears mounted within said casing; a camshaft rotatably mounted within said other compartment, the axis of rotation of said camshaft being substantially parallel to the axis of rotation of said bladed wheel, the camshaft carrying at least one cam, said cam having an arcuate camming surface; the bladed wheel being operatively connected to one of the gears of said train, a gear wheel fixed to said camshaft and meshing with a relatively slow-moving gear wheel in said train of reducing gears, whereby the camshaft rotates slowly, as compared to said bladed wheel, whenever the bladed wheel is rotated by liquid entering the inlet port under pressure; a strip of resilient material mounted adjacent each outlet port, one end of each of said strips being mounted at a point adjacent the inner wall of said other compartment, the other end of each of said strips being free and each of said strips being swingable about its point of mounting from a position in which it seals the outlet port it is mounted adjacent to a position in which it permits flow therethrough; and a spring bearing against each of said strips, said springs normally biasing said strips to occupy positions in which they seal the outlet ports; each of said strips extending beyond the outlet port which it is intended to seal, in a direction away from its point of mounting, for a distance sufficient to enable said cam to contact the strip and peel it back from its spring-pressed port-sealing position once during each complete revolution of the camshaft.

2. A control valve as defined in claim 1, in which only one cam is mounted on said camshaft and said one

cam contacts each of said strips, and thus opens each of said outlet ports, once during each complete revolution of said camshaft; and in which said outlet ports are equidistantly spaced around said other compartment and said one cam is of such width that, as it releases one of said strips, it contacts and begins to peel open the next-adjacent strip in the direction of rotation of the camshaft.

3. A control valve as defined in claim 1, in which a plurality of cams are carried by the camshaft, the number of cams being equal to the number of outlet ports, and the cams being mounted one above the other on the camshaft; and in which each of said strips, at the end thereof nearest the cams, is cut away so that each strip will be contacted only by the one cam which has been selected to peel back that strip during rotation of the camshaft.

4. A control valve as defined in claim 3, in which the total amount of arcuate camming surface provided by the plurality of arcuate camming surfaces is substantially 360 degrees, and in which the several camming surfaces are arranged without overlapping when viewed in the direction of the axis of the camshaft, so that one strip will be peeled open by one cam as another strip is released by its cam and spring-pressed to its port-sealing position, and one of said outlet ports will be opened at all times.

5. A control valve as defined in claim 4, in which said outlet ports are equidistantly spaced about said other compartment and said cams have equal arcuate camming surfaces, so that each outlet port will be opened for substantially the same interval of time, assuming substantially constant pressure in the case of the liquid entering the inlet port.

6. A control valve as defined in claim 4, in which said outlet ports are equidistantly spaced about said other compartment, but some of said cams have arcuate camming surfaces of greater length than the others, to provide for flow through the various outlet ports for different time intervals.
